UNITED STATES PATENT OFFICE.

WILLIAM ZENO STUART, OF WOOLSON, IOWA.

ROTARY ENGINE.

SPECIFICATION forming part of Letters Patent No. 712,105, dated October 28, 1902.

Application filed September 3, 1902. Serial No. 121,994. (No model.)

To all whom it may concern:

Be it known that I, WILLIAM ZENO STUART, a citizen of the United States, residing at Woolson, in the county of Jefferson and State 5 of Iowa, have invented a new and useful Rotary Engine, of which the following is a specification.

This invention relates to certain improvements in rotary engines, and has for its principal object to provide an engine combining to some extent the principles of a rotary and a reciprocating engine, a portion of the actuating fluid being introduced between a fixed and a movable surface disposed on lines parallel with each other and the movable surface being forced partly in a direction at right angles to the plane of the fixed surface and partly in a substantially circular path to follow the course of the purely rotary member 15 of the engine.

A further object of the invention is to construct a device of this character in which an angular piston in the form of an equilateral triangle may be forced to travel in a similar-shaped cylinder by the introduction of steam or other fluid into the three chambers formed between the sides of the piston and the adjacent walls of the cylinder.

With these and other objects in view the invention consists in the novel construction and arrangement of parts hereinafter described, illustrated in the accompanying drawings, and particularly pointed out in the appended claims, it being understood that various changes in the form, proportions, size, and minor details of the structure may be made without departing from the spirit or sacrificing any of the advantages of the invention.

In the accompanying drawings, Figure 1 is a perspective view of a rotary engine constructed in accordance with the invention. Fig. 2 is a longitudinal sectional elevation of the same. Fig. 3 is a transverse sectional elevation of the same on the line 3-3 of Fig. 2. Figs. 4 and 5 are detached perspective views of the piston member of the engine. Fig. 6 is a detail perspective view of one of the piston-guides. Fig. 7 is a detail perspective view of the reversing-valve detached. Fig. 8 is a view of a modified form of piston. Similar numerals of reference are employed

to indicate corresponding parts throughout the several figures of the drawings.

The cylinder 10 is in the form of an equilateral triangle and provided at its upper portion with a steam-chest 11, to which are connected steam supply and exhaust pipes 12 and 13, respectively. From the cylinder to the central portion of the chest extend two passages 14 and 15, which preferably lead through the walls of the cylinder, said passages terminating within the steam-chest in alignment with the ports of a valve 17 of cylindrical form, said valve having two ports 18, either 60 of which may be placed in communication with the steam-supply pipe 12 to admit steam to either of the passages 14 or 15 and being further provided with two ports 19, which may be similarly moved into alignment with the ports leading to the cylinder for the purpose of connecting the latter to the exhaust-pipe 13. This constitutes a reversing mechanism and permits the introduction of the steam through either of the cylinder-passages and its exhaust through the opposite passage. The valve is provided with a stem 21, extending to a point outside the steam-chest and secured to an operating-lever 22, having a latch-lever 23 of the usual construction and adapted to lock the lever to a notched bar 24 in either of the two positions of the valve, or the lever may be moved to a vertical position to cut off the flow of steam to the cylinder and stop the engine. Extending 85 through the cylinder is a shaft 25, provided at one end with a balance-wheel 26 and at the opposite end with a belt or other wheel 27 for the transmission of power. In the cylinder is arranged a piston 30 31, the member 30 being substantially in the form of an equilateral triangle of less area than the cylinder and provided with a centrally-disposed circular opening for the reception of the piston member 31. At the juncture of 90 each two sides of the triangular piston is a transversely-disposed knuckle 32, adapted for the reception of one end of a connecting-link 33, the opposite end of which has a similar knuckle 34, pivoted to the recessed edge 100 of a sliding block or plate 35. The bars or plates 35 are adapted to guiding-openings 36, one of which is disposed at each corner of the cylinder, and said blocks are moved into and

out of their respective recesses as the piston travels, the link-blocks 33 permitting a movement of the piston until its angular walls are successively moved against the adjacent walls 5 of the cylinder. The cylinder and piston walls form three steam-spaces, which are separated from each other by the links 33 and sliding blocks 35, the piston, links, and sliding blocks being of equal width and fitting 10 snugly between the vertical walls of the cylinder. On the shaft is mounted the circular member 31 of the piston, the center of this member being eccentric to the shaft and adapted to revolve in a circular opening 15 formed in the triangular member 30 of said piston. The member 31 is in the form of a disk and is provided with diametrically opposed abutments 40 and 41, which travel in the circular opening in the triangular portion 20 of the triangular piston. These abutments divide the steam-space into two semicircular chambers 42 and 43, of which either may form the steam and the other the exhaust chamber, and from these chambers extend a 25 plurality of ports 44, one of which leads to each of the steam-spaces formed by the cylinder and the adjacent angular face of the piston member 30. The piston member 31 extends laterally to the side walls of the cylinder, and in the opposite sides thereof are 30 annular grooves 47 in alignment with the two cylinder-ports 14 and 15, the groove at one side of the piston being in constant communication with the steam-passage 14 and the 35 groove at the opposite side of said piston in communication with the steam-passage 15. Extending upwardly from these annular grooves are steam-passages 48, terminating in oppositely-faced ports 49 and 50 at the opposite side of the abutment 40, the arrangement being such that steam from one of the cylinder-ports will enter one of the semicircular steam-spaces 42 43 and be discharged 40 through the opposite port and passages to the 45 exhaust-pipe 13.

In the operation of the mechanism, the parts being in the position shown in Fig. 2, steam is passing from the pipe 14 through the steam-passage of the cylinder and the corresponding 50 passage of the revoluble piston member 31 and issuing from the steam-port 49 to the semicircular steam-space 42, the steam passing through the opened port 44 to the space between the angular side of the piston member 30 and the adjacent walls of the cylinder. 55 At this time the revoluble piston member 31 is moved in the direction opposite to that indicated by the arrow, which shows the course taken by the steam, and the angular piston member 30 is moving in the direction of the opposite angular wall of the cylinder. At the same time steam is exhausted into the semicircular steam-space 43 through the open port 44 at the left-hand side of the angular piston member and 60 passing through the abutment-port 50 and thence through the several steam-passages to the exhaust-pipe 13. During this movement

steam has been confined within the lowermost steam-chamber between the bottom of the angular piston and the bottom of the cylinder 70 and by its expansion assists the steam entering the right-hand steam-chamber to force the angular piston to the left, and this movement is also assisted by the rotative movement of the revoluble piston member 31. As 75 soon as the abutment 41 passes the port 44 leading to the lowermost steam-chamber the latter will begin to exhaust and steam will pass to the exhaust-port 50, while the angular piston will receive a downward movement 80 from the pressure of steam in the right-hand steam-chamber and the steam admitted to the left-hand steam-chamber after the abutment 40 passes the steam-port leading to said steam-chamber. The movement of the parts 85 is permitted by the sliding of the bars 35 and the swinging movement of the links 33, so that the engine-shaft will receive a continuous circular movement so long as steam is supplied. 90

The engine may be operated in either direction by merely changing the position of the cylindrical reversing-valve 17, the operation of the parts being precisely the same as that previously described. 95

In some cases I may employ a revoluble piston member with but one abutment, as shown in Fig. 8, the surface of the piston member opposite the abutment being in contact with the wall of the circular recess in the 100 triangular piston.

Having thus described my invention, what I claim is—

1. The combination in an engine, of a cylinder in the form of an equilateral triangle, 105 a shaft extending through the cylinder, and a piston comprising two members of which one is of a shape corresponding to that of the cylinder and the other in the form of a cylindrical body secured to and rotating with the 110 shaft.

2. The combination in an engine, of a cylinder in the form of an equilateral triangle, 115 an angular piston member disposed within the cylinder and provided with a centrally-arranged circular recess, a shaft, a cylindrical piston member fitted within the circular recess and eccentrically mounted on the shaft, and steam inlet and exhaust passages extending through the cylindrical and the angular 120 piston members.

3. The combination in an engine, of a cylinder of angular form, a piston member also of angular form but of less area than the cylinder, 125 said angular piston having a centrally-disposed circular recess, a shaft, a cylindrical piston member fitting within said circular recess and eccentrically mounted on said shaft, abutments carried by said cylindrical member and dividing a portion of the recess into 130 steam and exhaust chambers, ports leading therefrom to the steam-spaces between the angular walls of the piston and the adjacent walls of the cylinder, and steam and exhaust

passages leading through the cylindrical piston member and terminating in ports at one of the abutments.

4. The combination in an engine, of an angular cylinder having at each angular corner a guiding-recess, a sliding block adapted to each recess, an angular piston member disposed upon the cylinder, links connecting the piston member to the blocks and serving in connection with said blocks to divide the interior of the cylinder into three separate steam members, a shaft extending through the cylinder, a cylindrical piston-body mounted on the shaft and adapted to a similarly-shaped recess within the angular piston member, and steam inlet and escape passages formed in both piston members.

5. The combination of the cylinder in the form of an equilateral triangle and provided with steam inlet and escape passages, a shaft, a cylindrical piston member mounted eccentrically on the shaft and provided with diametrically - opposed abutments, steam - pas-

sages extending through said piston member and terminating in oppositely-facing steam-ports at the opposite sides of one of said abutments, annular grooves formed in the sides of said piston member and with which the steam-passages of both the cylinder and the piston member communicate, the piston member in the form of an equilateral triangle being provided with a central opening for the reception of the circular piston member and its abutments, steam-ports leading through the piston member from the central opening to the outer walls of said angular piston, slideable blocks arranged at the corners of the cylinder, and links connecting said blocks to the angular piston member.

In testimony that I claim the foregoing as my own I have hereto affixed my signature in the presence of two witnesses.

WILLIAM ZENO STUART.
